Primary Examiner — Catheri Oliver-Garcia(74) *Attorney, Agent, or Firm* — Smith, Gambrell & Russell(57) **CLAIM**

The ornamental design for a multiple arm fishing rig, as shown and described.

DESCRIPTION

FIG. 1 is a perspective view of the multiple arm fishing rig with the arms spaced from each other;

FIG. 2 is an elevation view of a first side of the multiple arm fishing rig showing a center arm and the two nearest lateral arms. The opposite side of the lure would be a mirror image of the FIG. 2;

FIG. 3 is a top plan view of the multiple arm fishing rig showing a center arm and the two uppermost arms;

FIG. 4 is a bottom plan view of the multiple arm fishing rig showing a center arm and the two lowermost arms;

FIG. 5 is a front elevation view of the multiple arm fishing rig showing the arms spaced from each other; and,

FIG. 6 is a rear elevation view of the multiple arm fishing rig showing the arms spaced from each other.

1 Claim, 5 Drawing Sheets
